J. W. POLLOCK,
CONCENTRATOR.
APPLICATION FILED JAN. 22, 1920.

1,379,417.

Patented May 24, 1921.

UNITED STATES PATENT OFFICE.

JOHN W. POLLOCK, OF SAWTELLE, CALIFORNIA.

CONCENTRATOR.

1,379,417.

Specification of Letters Patent. Patented May 24, 1921.

Application filed January 22, 1920. Serial No. 353,375.

To all whom it may concern:

Be it known that I, JOHN W. POLLOCK, a citizen of the United States, and a resident of Sawtelle, in the county of Los Angeles 5 and State of California, have invented a new and Improved Concentrator, of which the following is a full, clear, and exact description.

This invention relates to a certain novel 10 construction of riffles and amalgamating trays for use in placer mining. By means of my invention a very high percentage (98%) of flour gold may be saved, as well as the black sand, which latter is valuable 15 for its iron.

This specification is an exact description of one example of my invention, while the claims define the actual scope thereof.

Reference is to be had to the accompanying 20 drawings forming a part of this specification, in which similar characters of reference indicate corresponding parts in all the views.

Figure 1 is a section on the line 1—1 of 25 Fig. 3.

Fig. 2 is a plan view, and

Fig. 3 is a section on the line 3—3 of 30 Fig. 1.

a indicates the sluice, which may be single 35 or double, as desired. It is here shown as a single sluice. Formed in the bottom *a'* of the sluice are one or more cavities *a²*, these cavities slanting downward from one side of the sluice toward the other, and running 40 through the side wall (see Fig. 3). Placed in the cavities *a²* are the removable amalgamating trays *b*, which occupy the full area of the cavities and project through the open side of the sluice, as shown, these trays *b*, 45 slanting down in accordance with the slant of the bottom of the cavities *a²*. Placed over the tray is the riffle *c*. This riffle is preferably formed of a steel sheet perforated as shown. The form of the perforations 50 may be varied to suit the nature of the material worked. The riffle is provided with transverse depressions or riffles proper *c'*. A "grizzly" or coarse screen *d* is adapted to be placed over the bottom of the sluice 55 and over the riffle, and is provided with a plurality of transverse upstanding ribs *d'* which serve also as riffles.

Transverse strips *e* are disposed on the sluice *a'* to overlap the ends of the riffle *c*, 60 so as to prevent any sand from lodging between the riffle and the sluice. A strip of

cloth can be conveniently secured beneath each strip *e*, thus helping materially to collect small values that lodge at the ends of the riffle. 60

For the purpose of facilitating the removal of the amalgamating tray *b*, I have provided a handle *b'*, secured to the tray on the under side of the same.

I have here shown one riffle and one amalgamating tray; in practice, however, I shall employ a number of these elements in each sluice. In the operation of the invention, the material to be worked is thrown or washed into the sluice and caused to run 70 down the same with a stream of water. The coarse, valueless materials will pass over the top of the grizzly, but the flour gold and black sand will drop through the grizzly and drift along the bottom of the sluice. 75 The material, in passing over the riffles, will be agitated, and the particles of flour gold and black sand escape through the riffles into the amalgamating trays, which are constructed of copper with a covering of quicksilver or mercury. This causes the flour gold to adhere to the trays, while the substances remaining pass off from the lower end of the trays, as indicated by the arrow 80 in Fig. 3. A small concentrate box should 85 be placed under each amalgamating tray to receive the discharge thereof, and these concentrates may, from time to time, be shoveled back into the sluice at various points along the length thereof, so as to insure a collection 90 of all the values, but always below the first riffle. This apparatus enables the miner to save all the black sand, in addition to collecting the flour gold, the black sand being first quality iron with a high market value. 95

The trays *b* may be readily removed to collect the gold, and other trays be slipped back in their places. This operation may be effected in a very short time (one minute) thereby avoiding stopping the operation of 100 the sluice for any length of time. The trays are removed by sliding them transversely of the sluice through the open side wall thereof, and in and out of the cavities *a²*. The riffles *c* may also be removed at will by simply 105 lifting them upward from their active position. Any number of indentations or riffles proper *c'* may be formed in the riffle *c*, and the sluice may be of any length desired and fitted with any number of riffles and amalgamating trays. 110

Various changes in the form and details

of my invention may be resorted to at will without departing from the spirit of my invention, hence I consider myself entitled to all forms of the invention as may lie within 5 the intent of my claims.

Having thus described my invention, I claim as new and desire to secure by Letters Patent;

1. A concentrator comprising a longitudinally inclined sluice having a transversely inclined, longitudinally horizontal cavity in its bottom wall and a discharge passage in one of its side walls at the lower side of said cavity, an amalgamating tray disposed in 10 said inclined cavity to permit of the discharge therefrom, through said discharge passage and to effect an equal distribution of values deposited thereon, and a riffled screen covering the cavity and superposed 15 to the amalgamating tray.
2. In a concentrator, the combination with a longitudinally inclined sluice having an opening in one of its side walls and a longitudinally horizontal depression in the bottom wall thereof communicating with the opening of said depression having its lower wall transversely inclined downwardly toward the opening, of an amalgamating tray 20 adapted to be arranged on the lower wall of said depression and projecting through the opening to permit of the discharge of water therefrom and to effect the equal distribution 25 of values deposited on said tray.

3. A concentrator comprising a longitudinally inclined sluice provided with a cavity 35 arranged in the bottom wall thereof, said cavity having a transversely inclined lower wall arranged in a horizontal plane longitudinally, said sluice having a discharge passage disposed in the side wall at the 40 lower side of the cavity, an amalgamating tray adapted to be arranged in the cavity and resting on the lower wall thereof to dispose the same at a transverse angle for discharging the water therefrom and for effecting an equal distribution of the deposited values thereon and a riffle screen covering 45 said cavity and superposed with respect to the amalgamating tray.

4. In a concentrator, the combination 50 with a longitudinally inclined sluice having an opening in one of its side walls, a depression in the bottom wall thereof communicating with the opening, said depression having its lower wall inclined transversely and 55 downward toward the opening, said lower wall being horizontally disposed longitudinally thereof, and a riffle screen covering the depression, of an amalgamating tray 60 adapted to be arranged on the lower wall of said depression and projecting through the opening to permit of the discharge of water therefrom and effecting equal distribution of values deposited on said tray.

JOHN W. POLLOCK.
